Inventor.

A. R. Milner

UNITED STATES PATENT OFFICE.

ALBERT R. MILNER, OF CLEVELAND, OHIO, ASSIGNOR TO THE MILNER MUSIC COMPANY, OF SAME PLACE.

ADJUSTABLE PIANO-STOOL.

SPECIFICATION forming part of Letters Patent No. 471,184, dated March 22, 1892.

Application filed July 5, 1890. Serial No. 357,921. (No model.)

To all whom it may concern:

Be it known that I, ALBERT R. MILNER, a citizen of the United States, residing at Cleveland, in the county of Cuyahoga and State of Ohio, have invented certain new and useful Improvements in Adjustable Piano-Stools; and I do hereby declare that the following is a full, clear, and complete description thereof.

The nature of my invention relates to the construction and arrangement of the various parts of an adjustable piano-stool, as herein-after fully explained, whereby the neatness, durability, and strength of the stool are enhanced.

15 That the invention may be seen and fully understood by others reference will be had to the following specification and annexed drawings, forming part thereof, in which—

Figure 1 is a perspective view of the complete stool. Fig. 2 is a plan view of the sleeve and seat-attaching plate. Fig. 3 is a vertical section of the entire stool. Fig. 4 is a side elevation of one of the detachable legs, and Fig. 5 a plan view of the leg-brace.

25 Like letters of reference designate like parts in the specification and drawings.

A hollow casting or sleeve A, having a seat-attaching plate on its upper terminal, said plate being preferably an integral part of the sleeve A, is screwed, bolted, or otherwise rigidly attached to the seat. The bore of the upper portion of the sleeve A is polysided, the one herein described being hexagonal. A hexagonal nut G, Fig. 3, is dropped into the sleeve A from the upper side before the seat is attached thereto. The nut is therefore easily removed and replaced by a duplicate at a trifling cost in case of wear. Two semicircular castings F F, forming a two-part sleeve, 30 are then placed in the sleeve A on top of the hexagonal nut G. The upper terminals of the castings F F, being in contact with the seat of the stool when said seat is attached to the plate, hold the nut in place. The rod D, threaded part way down from its upper end, passes up through the opening in the sleeve A, as shown in drawings, entering the nut G. The sleeve A extends down around the rod D, hiding the threaded portion of said rod 45 when the seat is lowered, raised to its extreme height, or at any intermediate point, thereby excluding all dust or sand. Said sleeve turns freely around the rod D.

My improved stool may have three or more legs, the one shown in drawings having three, 50 which are attached to the rod D in the following described manner: The legs are each substantially the form shown in Fig. 4, having a lug or hook J, which is an integral part thereof. Said hook is inserted in the eye c at the outer 55 terminal of an arm of the leg-brace C, Fig. 5. There are the same number of arms to said brace as there are legs to the stool, each arm having a similar eye, as shown in Fig. 5. The upper terminals of the legs are then brought 60 in contact with each other and the ring H placed over them, holding them together, thereby locking the legs rigidly to the brace, resultant from the pressure of the shoulder O of the leg on the shoulder Q of the leg-brace 65 and the peculiar form of the hook J. The upper terminals of the legs are so formed that when brought in close contact with each other they will form a circular opening within the ring H. The rod D, having a shoulder L, Fig. 70 75 3, thereon, passes down through the ring H and the circular opening formed at the upper terminals of the legs B B B, said shoulder coming in contact with the ring H, and the lower end M of the rod D will enter the hole 80 N, Fig. 5, in the leg-brace C. A screw is then threaded into the lower end of the rod D from beneath the leg-brace C, causing a tension or strain on the legs B B B, resultant from the drawing of the shoulder L on the ring H; or 85 a nut may be threaded on the lower end of the stem and bear on the under side of said brace and still adhere to the nature of my invention. It will readily be seen that the tension thus caused on the legs and brace will 90 form a perfectly rigid frame. The thread on the upper portion of the rod D may be square or it may be a V-thread, a square thread, however, being preferable. The sleeve A, extending down over the rod D in the manner herein 95 described, prevents sand, dust, &c., from entering the thread on said rod. Consequently there is less wear than in the ordinary stool, where the rod is attached to the seat and screws down into the standard.

Having described my invention, what I claim, and desire to secure by Letters Patent, is—

1. In an adjustable piano-stool, the sleeve 5 A, rigidly attached to the seat, the upper portion of the bore of said sleeve being polysided in form, in combination with a polysided nut G and two-part sleeve F F, arranged within said sleeve A in conjoint operation with the 10 screw-rod D, legs B B B, and leg-brace C, arranged substantially in the manner and for the purpose set forth.

2. In a piano-stool, a seat having a sleeve attached to the under side thereof, a supporting-rod the upper end of which is contained 15

in said sleeve, a shoulder formed on the rod midway of the length, a ring bearing against the shoulder, legs provided at their upper ends with projections fitting under the said ring and near their lower ends with hooks, a leg-brace provided with a central hub adapted to receive the lower end of the supporting-rod and having radial arms with eyes formed in the outer ends thereof, which engage the hooks on the legs, and means for detachably securing the brace to the rod. 20 25

ALBERT R. MILNER.
